SAFETY RAZOR

John W. Ashworth, New York, N. Y.

Application April 5, 1930, Serial No. 441,873
Renewed July 20, 1933

4 Claims. (Cl. 30—12)

This invention relates to safety razors and more particularly to that general type of safety razor wherein the handle is adjustable with respect to the blade, i. e., is rotatably adjustable 5 with respect to the axis of the clamping device which holds the blade between the guard and clamping plate.

The object of the invention is to provide a construction to permit more ready detachment 10 of the blade and clamping plate in order that the same may be cleaned after shaving and without disconnecting the clamping plate from the handle and to also provide in such a structure an assembly of parts which will permit of the 15 detachment of all of said parts in the event that it is desirable to do so.

A further object of the invention is to provide a novel blade construction so constituted that it will not crack or break along its longitudinal 20 medial line. The breaking of razor blades as now made very commonly occurs thereby rendering the blade unfit for use and in numerous cases resulting in injury to the person using the blade at the time. The blade of the present invention 25 in contradistinction is so constructed that the possibility of breakage is minimized.

The invention is susceptible to different practical embodiments, but in one of its preferred practical forms, the clamping and guard plates 30 are adapted to be held together in clamping relation with respect to the blade and also serve to hold a handle in cooperation with the rest of the parts through the employment of a screw adapted to thread through alined apertures in 35 the handle, guard and clamping plate and to pass loosely through a hole in the blade. The screw, however, is so constituted that while it must be screwed through the holes of the respective parts in order to effect assembling or dis- 40 mantling of the parts, it will in this clamping position have a screw threaded connection with only the clamping plate so that it may readily turn with respect to the other parts in order to produce a tight clamping action. When it is 45 desired to remove the blade for cleaning it is thus only necessary to retract the screw sufficiently to release the clamping plate. This plate and the blade may then be removed, while the 50 guard and handle remain affixed with respect to one another and will not be able to independently fall on the floor as is now generally the case in conventional safety razors. The connection between the guard and handle however is 55 of a swivel type and relatively loose when the

blade is removed, so as to permit cleaning of the parts without necessarily dismantling them.

An important feature of the present invention resides in the fact that the handle is provided with a foot positioned in oblique relation to the axis of the handle and serving to offset such axis to substantially the edge of the blade, so that there will be no tendency during the operation of the razor to rock. By this arrangement, a smooth shave with a uniform cut is more readily attained and without depending entirely upon the guard as is the case in conventional razors. 60

In order to maintain the handle in proper angular relation to the blade, the foot is provided with a projection adapted to cooperate with depressions in the back of the guard so that when the parts are clamped together the handle can- 65 not shift.

Features of the invention, other than those specified, will be apparent from the hereinafter 70 detailed description and claims, when read in conjunction with the accompanying drawing.

The accompanying drawing illustrates different practical embodiments of the invention, but the constructions therein shown are to be under- 75 stood as illustrative, only, and not as defining the limits of the invention.

Figure 1 shows a razor embodying the present invention partly in central section and partly in 80 side elevation.

Figure 2 shows the razor of Figure 1 with the parts dismantled.

Figure 3 is an underneath plan view of the structure shown in Figure 1.

Figure 4 is a perspective view of the clamping 85 plate.

Figure 5 is a perspective view of the preferred form of blade.

Figure 6 is a like view of a modified form of 90 blade embodying this invention.

Figure 6a shows a safety razor blade of conventional form, the same being illustrated to more clearly illustrate the difference between the present invention and a conventional blade.

Figure 7 is a back view of a modified form of 95 handle.

Figure 8 shows a side elevation of a portion of a handle and foot and a clamping screw, with means to secure the screw against detachment from the handle.

Figure 9 is a section on the line 9—9 of Figure 8.

Figure 10 is a view similar to Figure 9 but showing a modified form of construction.

Figure 11 is a view similar to Figure 8 but 110

showing a further modified form of construction.

Referring to the drawing, 1 designates a guard plate, 2 the clamping plate, 3 the blade, 4 the handle and 5 the clamping screw. The guard is similar in shape and configuration to the conventional guard although it preferably has flat faces, is provided centrally with a threaded opening 6 and at its ends has rectangular cut outs 7 shown best in Figure 3. Arranged in annular series 10 about the central opening and in the back face of the guard are depressions or holes 8, the purpose of which will be hereinafter more fully explained.

The clamping plate is of substantially conventional form except it has a central threaded opening 9, while the studs 10 are preferably square in cross section although they may be round as is usual. The handle 4 is provided with a foot 11 positioned in oblique relation to the axis 20 of the handle and this foot has a threaded opening 12 positioned from the handle a distance approximately equal to one half the width of the blade. The clamping screw 5 is provided with an appropriate finger piece 13 to which is attached 25 a shank having a threaded end portion 14 and an unthreaded intermediate portion 15. The threaded holes 9, 6 and 12 are preferably of the same diameter and have a like thread appropriate to fit the threaded portion 14 of the screw. 30 It is to be noted, however, that the axial dimension of the threaded portion 14 is substantially equal to the thickness of the clamping plate. Thus in assembling the parts the threaded portion 14 is screwed successively through the holes 35 12 and 6, thence loosely through the hole in the blade and then screwed into the hole 9. While it is being screwed into the hole 9, the unthreaded part 15 is extending through the holes 12 and 6 and consequently the screw may be tightened 40 within the hole 9 to draw the parts firmly together to clamp the blade in place. However, if it is desired to remove the blade for cleaning, it is only necessary to unscrew the screw sufficiently to release the clamping plate 2 and the clamping plate may then be removed and the blade lifted off. The fact that the holes 6 and 12 are threaded will preclude these parts from separation even when the blade is removed unless at 45 the option of the user, the screw is removed from one or both of these parts. It will thus be seen that the blade may be removed for cleaning while leaving the handle and guard secured together.

It will be noted that by the construction shown, the handle is adjustable in an arcuate path 55 about the axis of the screw and to permit of the locking of the handle in any desired position, the foot is provided with a pin or projection 16 adapted to cooperate with any one of the depressions 8 to lock the handle in adjustable position when the screw is tightened. The foot at the base of the handle may be of the fan shaped contour as shown in Fig. 3 or may be in the form of a circular plate or disk as illustrated in Figure 7 or of any other suitable contour.

65 I have hereinbefore stated that the studs 10 are preferably square and I have particular reasons for this preference. In Figure 6a, I have shown the conventional safety razor blade with round roles therein. Such a blade is structurally weak along its medial line 17 because there is less stock along this line than in any other part of the lateral dimension and blade. Consequently when an attempt is made to bend such a blade it will naturally tend to take the complete bend 70 along the medial line 17 and as a result the blade 75

breaks. The breaking of blades along this line is common knowledge.

According to the present invention, therefore, I so construct the blade that instead of having a weak central section along a line, I make this central section relatively weak throughout a relatively broad band with the result that when the bending occurs, it will not all tend to take place along a single line, but will be distributed without the relatively broad band and as a result breakage is practically unknown with a razor of this type. This I am able to accomplish by forming the holes of the blade of rectangular cross section. Thus in Figure 5 the central hole 18 is of elongated rectangular cross section, while the end holes are in the form of reentrant notches 19 of rectangular cross section. By so cutting out the blade, there is left between the cut outs strips 20 extending transversely of the blade between the lines 21 which mark the lateral edges of the cut outs and between the lines 21 there is thus formed a band or weak section which is relatively wide and throughout which the bending stresses are so distributed that breaking will not occur. The same general arrangement is illustrated in Figure 6 in modified form, where the central hole 18a and the end holes 19a are of rectangular section for the purposes stated. The blades of either Figures 5 or 6 may be used in conjunction with the razor illustrated in the remaining figures and the square studs 10 will cooperate properly with either the cut outs 19 or the holes 19a.

In Figures 8 to 11, I have illustrated somewhat modified forms of constructions. In these forms of construction, the clamping plate and guard are secured together by means of a threaded post mounted on the clamping plate as in conventional razors and adapted to extend through the blade, guard and handle without threaded connection 110 with any of them. Upon this threaded post is adapted to be screwed a nut 22 and in the figures referred to means is provided to secure the nut to the handle so that the nut will not fall off or become lost when the blade is removed.

In the structure of Figures 8 and 9, the nut 22 is secured to the handle 4 by a spring wire clip 23 which embraces the nut as shown and has its ends extending into a perforation 24 in the handle. In Fig. 10, the same result is accomplished 115 by bending a wire 25 about the nut 22 and then passing the wire through a perforation 26 in the handle and thereupon heading over or bending out the ends of the wire as shown at 27 to hold the parts together. In the structure of Fig. 11, 120 the nut 22 is provided with a shank 28 which extends through the perforation in the foot of the handle and is upset or headed over as shown at 29 to preclude its removal from said foot while permitting free rotation of the nut.

In all of the structures which I have described, means is embodied for securing the nut or screw to the handle while in the preferred form of Figures 1 to 3, the screw is normally maintained against displacement from both the handle and guard. This latter construction is accomplished in Figures 1 to 3 and constitutes the preferred form of this invention, because of its marked simplicity, high efficiency and economy of manufacture.

The drawing and foregoing description set forth the present invention in its preferred practical form, but the invention is to be understood as fully commensurate with the appended claims. The holes 6 in the guard may be threaded all 145

the way through, but, as shown in the drawing, it is threaded approximately half way through and then slightly enlarged, so as to give a wide degree of swivel movement between the guard 5 and the handle when the clamping plate 2 is removed to thereby permit the parts to be wiped off clean and dry without dismantling the guard from the handle by removal of the screw.

Having thus fully described the invention, what 10 I claim as new and desire to secure by Letters Patent is:

1. A safety razor embodying a clamping plate, a guard, and a handle having an offset foot positioned in oblique relation to the handle, said 15 plate, guard and foot having alined threaded openings, and a clamping screw extending through said openings and threaded into the clamping plate, that portion of the screw extending through the perforations of the guard 20 and foot being unthreaded.

2. A safety razor embodying a clamping plate, a guard, and a handle arranged in superimposed relation with a blade between the clamping plate and guard, said clamping plate, guard and handle 25 having alined threaded apertures, and a screw extending through said apertures in the handle, guard and plate in succession and being smooth and unthreaded for the portion thereof which extends through the handle and guard, to permit 30

of release of the clamping plate and blade without releasing the guard from the handle.

3. A safety razor embodying a clamping plate and a guard, both of which are provided with alined threaded apertures, a handle, a threaded member secured to the handle and extending through the apertures of the guard and clamping plates, the threads of said member interiorly of the aperture of the guard being mutilated so as not to engage with the threads of the guard, whereby the clamping plate may be released from the threaded member without releasing the guard 80 from said member. 85

4. A safety razor embodying a clamping plate, a guard, and a handle arranged in superimposed relation with a blade between the clamping plate, guard and handle, said clamping plate, guard and handle having alined threaded apertures, a screw 90 extending through said apertures in the handle, guard and plate in succession and being smooth and unthreaded for the portion thereof which extends through the handle and guard, to permit 95 of release of the clamping plate and blade without releasing the guard from the handle, the threaded aperture in the guard plate being countersunk or enlarged at its end adjacent the blade to permit a free swivel movement between the guard and the handle. 100
